DESIGN FOR A SIGN OR ARTICLE OF A SIMILAR NATURE

William C. Westphal, Cleveland Heights, Ohio

Application August 2, 1933. Serial No. 48,908

Term of patent 3½ years

To all whom it may concern:

Be it known that I, WILLIAM C. WESTPHAL, a citizen of the United States, residing at Cleveland Heights, in the county of Cuyahoga and State of Ohio, have invented a new, original, and ornamental Design for a Sign or Article of Similar Nature, of which the following is a specification, reference being had to the accompanying drawing, forming part thereof.

The figure is an elevation of a sign, showing my new design.

My design consists of a center field of white surrounded by a border, said center field bearing

fanciful figures, namely a male worker and a female worker, and between these figures horizontal bars spaced to provide areas for numerical figures. The border, figures and bars are in contrasting colors as indicated on the drawing.

It is contemplated to use this design for flags, pennants, signs, emblems and articles of a similar nature.

I claim:

The ornamental design for a sign or article of a similar nature, as shown and described.

Signed by me this 31st day of July, 1933.

WILLIAM C. WESTPHAL.
